UNITED STATES PATENT OFFICE.

LEWIS E. WATERMAN, OF ROCKFORD, ILLINOIS, ASSIGNOR TO EMERSON MANUFACTURING COMPANY, OF ROCKFORD, ILLINOIS, A CORPORATION OF ILLINOIS.

WHEEL-BOX.

SPECIFICATION forming part of Letters Patent No. 740,341, dated September 29, 1903.

Application filed May 18, 1903. Serial No. 157,659. (No model.)

To all whom it may concern:

Be it known that I, LEWIS E. WATERMAN, a citizen of the United States, residing at Rockford, in the county of Winnebago and State of Illinois, have invented certain new and useful Improvements in Wheel-Boxes and Methods of Making Same, of which the following is a specification.

The object of this invention is to construct a wheel-box having one end closed by the use of a chaplet in order that a dust-proof box may be had and one that will hold oil.

In the accompanying drawings, Figure 1 is an isometrical representation of my improved wheel-box. Fig. 2 is a vertical section of the closed end. Fig. 3 is an isometrical representation of the chaplet. Fig. 4 is a transverse section on dotted line *a*, Fig. 2.

In the manufacture of the wheel-boxes having one end closed the core is located in the mold and supported by one end only, and when the metal is poured into the mold it will warp or bend the core, so that the thickness of metal composing the outer wall of the box will not be uniform, thereby forming the opening diagonally to the lengthwise direction of the box which binds against the axle in its rotary motion.

The main portion 1 of the wheel-box is cylindrical in outline, having a central cylindrical opening 2, extending in its lengthwise direction. At Fig. 3 is shown the chaplet comprising a cylindrical section 3, having a series of radially extending projections 4. This chaplet is located near the closed end of the box and the metal comprising the box embraces the chaplet, as shown at Figs. 2 and 4, so that the line of connection between the chaplet and the metal composing the box proper will be tight and hold oil as a lubricant for the axle and prevent the admission of dust and grit.

In the manufacture of my improved wheel-box the chaplet is formed with the core for the central opening of the box, the core is supported in the mold by one end in the usual

manner, and the projections 4 of the chaplet resting against the inner wall of the core serves to support the free end of the core centrally within the mold, and when the metal 50 composing the main portion of the wheel-hub is poured a union will be formed with the chaplet, so that when the core-sand is cleaned away the opening in the wheel-box will extend centrally in its lengthwise direction. 55

My improved wheel-box can be used in connection with wheels for different purposes, but is especially adapted for agricultural implements, and can be cast integral with the wheel without departing from the scope of my 60 invention.

I claim as my invention—

1. A wheel-box comprising the box proper having a solid end of the metal of which the box is composed, and a chaplet located inside 65 the end of the box, and having sections forming portions of the outer wall of the box.

2. A wheel-box comprising the box proper having a solid end of the metal of which the box is composed, and a chaplet located inside 70 the end of the box, and having sections forming portions of the inner wall of the box.

3. A wheel-box comprising the box proper and a chaplet in spider form held in place by the metal comprising the box proper. 75

4. A wheel-box comprising the box proper having a solid end of the metal of which the box is composed, and a chaplet located inside the end of the box having sections forming portions of the outer wall of the box and sections forming portions of the inner wall of the box. 80

5. A wheel-box comprising the box proper, and a chaplet held in place by the metal forming the box proper and alternate portions of 85 the chaplet forming alternate portions of the inner and outer walls of the box.

LEWIS E. WATERMAN.
